UNITED STATES PATENT OFFICE.

ALFRED ERNEST MACLACHLAN, OF MONTREAL, CANADA.

CIGAR EXTINGUISHER AND PROTECTOR.

No. 802,300.

Specification of Letters Patent.

Patented Oct. 17, 1905.

Application filed June 21, 1905. Serial No. 266,207.

To all whom it may concern:

Be it known that I, ALFRED ERNEST MACLACHLAN, of the city of Montreal, Province of Quebec, Canada, have invented certain new and 5 useful Improvements in Cigar Extinguishers and Protectors, of which the following is a full, clear, and exact description.

My invention relates to cigar extinguishers and protectors; and the object is to provide 10 an inexpensive device by which a partially-smoked cigar may be quickly extinguished and preserved until the smoker is ready to finish the part that remains.

It is often found necessary when entering a 15 street-car or a residence or between acts at a theater to throw away the unsmoked portion of a cigar, as the odor becomes offensive if a partially-burned cigar is carried loosely in the pocket. By the use of my device, which consists of a hollow cap and an elastic tube, the 20 burning end of the cigar is inserted into the cap, and the elastic tube is pulled over a portion of the cigar, so that air is excluded and the fire immediately extinguished. The cap 25 may then be placed in the vest-pocket and the cigar preserved without any disagreeable odor.

In the drawings which illustrate my invention, Figure 1 is a perspective view of the 30 elastic tube. Fig. 2 is a perspective view of the cap. Fig. 3 is a sectional view of the device, showing the elastic tube rolled up on the cap. Fig. 4 is a plan view of the device shown in Fig. 3. Fig. 5 is a plan view of the device 35 with a cigar inserted in the cap.

Referring to the parts, A represents a hollow cap of any suitable material closed at its apex and provided toward its open end with an exterior annular groove A'. The edge A² 40 of the groove adjacent the open end of the cap is slightly larger in circumference than the opposite edge, and the cap tapers slightly from the groove toward the open end, as shown at A³.

B is a tube of rubber or other suitable material open at both ends and slightly tapered toward its upper end, as shown at B'. The tube terminates at both ends in thickened rings B² and B³. A cigar C is shown in Fig. 5. The 45 tapered end of the tube is stretched over the open end of the cap until the thickened ring

B² fits into the groove A', and the tube is then rolled from its opposite end around the ring B³ until it assumes the position shown in Figs. 3 and 4. In this position it is prevented 55 from unrolling by the enlarged edge A² and may be carried in the pocket ready for use.

When it is desired to extinguish a lighted cigar and preserve the part that remains, the burning end is inserted in the open end of the 60 cap and the elastic tube unrolled over the cigar, as shown in Fig. 5. The air is thus entirely excluded and the fire is almost immediately extinguished. The cap with the cigar inserted may then be carried in the pocket until it is desired to smoke the part that remains.

My invention is simple and inexpensive in construction and economical in use.

Having thus described my invention so that the same may be readily understood by those 70 skilled in the art to which it appertains, what I claim, and desire to secure by Letters Patent, is—

1. A cigar extinguisher and protector comprising a hollow cap closed at its apex and having an exterior annular groove near its open end, in combination with an elastic tube provided at its ends with thickened rings, one of said rings being adapted to fit into the annular groove of the cap, substantially as described. 75

2. A cigar extinguisher and protector, comprising a hollow, conical cap, having an exterior annular groove adjacent its open end, in combination with an elastic tube having 85 one end adapted to fit into the annular groove of the cap, substantially as described.

3. In a cigar extinguisher and protector, a hollow, conical cap having an exterior annular groove near its open end, in combination 90 with an elastic tube, tapered at one end and terminating in a thickened ring adapted to fit into the annular groove of the cap, the other end being adapted to roll back upon itself toward the top, substantially as described. 95

4. In combination, a hollow, conical cap having an exterior annular groove so formed that the edge adjacent the open end of the cap is slightly larger in circumference than the opposite edge, and an elastic tube, tapered at 100 one end and terminating in thickened rings, the tapered end being adapted to fit over the

annular groove of the cap, substantially as described.

5. A cigar extinguisher and protector comprising a hollow, conical cap adapted to hold the end of a cigar, an exterior, annular groove near the open end of said cap, and an elastic tube having one end adapted to be detachably fitted into said groove and the other end adapt-

ed to partially envelop the cigar, substantially as described. 10

In witness whereof I have hereunto set my hand in the presence of two witnesses.

ALFRED ERNEST MACLACHLAN.
